UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

HOPPER-CAR-DOOR MECHANISM.

Application filed November 21, 1923. Serial No. 676,047.

In the drawings:

Fig. 1 is a side elevation of a railway hopper car equipped with the invention, certain portions being broken away to show the door locking and releasing mechanism parts mounted in service position on the car;

Fig. 2 is a plan view of a portion of the car with certain parts broken away to show the application of the door mechanism;

Fig. 3 is a vertical sectional view of the car taken on line 3—3 of Fig. 2, looking in the direction indicated by the arrows and showing the door mechanism assembly in locked position with novel tripping and locking pawl and actuating arm elements;

Fig. 4 is a similar view showing in full lines the door mechanism in released position just prior to the dropping of the doors and showing in dotted lines a portion of the door mechanism in the position taken when the doors are dropped.

Fig. 5 is a sectional view taken on line 5—5 of Fig. 1, looking in the direction indicated by the arrows and showing the crank shaft assembly and tripping and locking mechanism;

Fig. 6 shows the combination indicator and counter-balance portions of the door locking and releasing assembly; and

Figs. 7 to 12 inclusive represent the positions of the crank shafts at opposite ends of the doors, the sectional views corresponding to one on line 7—7 of Fig. 5, and show in Figs. 7 and 8 the relative positions of shaft lug and the lug on the sprocket wheel after the sprocket wheel has been rotated to the position shown in Fig. 3 just prior to the unlocking and tripping operation, and in Figs. 9 and 10, the relative positions of the lugs after the dropping of the doors, and Figs. 11 and 12 show the relative positions of the lugs on crank shaft and sprocket wheel when the doors have been raised and locked.

My invention relates to that class of hopper bottom cars used primarily in the ore carrying service and has for one of its objects the provision of door operating mechanism designed to drop the doors to discharge the lading and to raise and support them in closed position, such mechanism including suitable lost motion devices to permit the doors to drop without communicating such movement to the operating shaft, said lost motion devices being adapted for automatically locking and releasing the

crank arm elements of the door operating mechanism.

In the drawings, 10 represents a car of the hopper type having a single discharge opening in its bottom, the bottom being closed by a pair of doors 12 hinged at the car sides and meeting with their free edges at the longitudinal center of the car. The doors extend the entire length of the door opening and are provided with hinge members 13 secured to the inner longitudinal side sill members 14 of the car underframe 11.

The doors are provided at their ends with projecting portions 15 designed to permit attachment of the door links 16 to the door mechanism. The door links comprise the jaws 17 pivotally connected to links connected to the door projections 15 by pins 18, the yoke pieces 20 mounted on crank pins 21 having bearings in the crank frames 22, and link rods 23 pivotally secured to the yoke pieces 20 and pivotally and adjustably secured at their lower ends to the jaws 17. This arrangement permits free play of the door links throughout the full range of door travel and crank frame movement.

The crank frames 22 are pivotally journaled in bearing brackets 19 secured to the sloping end floor sheets 24 of the hopper 25. Journaled in the brackets 19 underlying the sloping end floors 24 of the hopper, the crank frames 22 are in condition to be actuated by the operating mechanism to rotate from their locking door supporting position shown in full lines in Fig. 3 to their released load discharging position shown in broken lines in Fig. 4. In their door supporting position the crank frames lie substantially parallel to the sloping end floor sheets of the hopper. In this position the link rods 23 lie in a plane passing through crank pin 21 and jaw pins 18 and inside of a parallel plane through the axial center of the crank frame trunnions 26, tending thereby to induce rotation of the crank frames toward the hopper end floors 24 and locking them against reverse movement until forced outwardly beyond the dead center of the parts whereupon such parts will move under the weight of the doors to release the doors to discharge the lading.

The operating mechanism comprises a pair of crank shafts 30 arranged transversely of the car and mounted adjacent the underside

of the sloping end floors 24 and journaled at their outer ends in bearings 31 secured to the outer longitudinal side sill members 32 and engaging at their inner ends with respectively adjacent crank frame trunnions 26. The crank shafts are provided at their outer ends with lugs 33 designed to engage lugs 34 on driven sprocket wheels 36 and 37 providing a loose connection between the crank shafts 30 and an operating shaft 35 to permit the dropping of the doors and rotation of the crank shafts 30 without communicating such movement to the operating shaft 35. The driven sprocket wheels 36 and 37 are loosely fitted to the crank shafts 30, as shown in Fig. 5, and are formed to interlock with the shaft lugs 33 for limited rotation on the crank shafts and to prevent shifting of the wheel longitudinally of the shafts. These sprockets are mounted in a plane adjacent the car side and are connected together by a continuous link belt mechanism 38 for the simultaneous operation of the crank frames 22 at opposite ends of the hopper, the link belt connection being so designed as to effect the relatively opposite rotation of the crank shaft sprockets, crank shafts, and crank frames 22, respectively. The operating shaft 35 extends from side to side of the car and has fixed thereon the driving sprocket wheel 39 adjacent and in line with the crank shaft sprocket 36 and engaged by the link belt mechanism 38 which is in engagement with the sprockets 36 and 37 also. Adjacent this driving sprocket 39 is fixed a ratchet wheel 40 designed to be engaged by a locking pawl 41 fixed to the adjacent end of a pawl shaft 42 parallel to the operating shaft 35 and also extending from side to side of the car and operable from either side. The pawl 41 is actuated by a handle 43, preferably integral with the pawl and serving as a counter-balance to either hold said pawl in engagement with the ratchet wheel 40 or out of contact therewith. The operating shaft 35 is provided with square ends to facilitate operations from either side of the car by means of a removable lever (not shown).

To insure positive movement of the crank frames 22 past their dead center locking positions during the door opening movement of the mechanism and to prevent premature dropping of the doors through the failure of the operating mechanism to assume its proper door locking dead center position, additional crank mechanism tripping and locking devices are provided. These devices form part of an assembly comprising mechanism automatically operable through the medium of the lost motion devices comprising the sprocket wheel 37 and the adjacent crank shaft 30.

The crank arm tripping and locking assembly comprises a pair of parallel tripper shafts 50 and 51 arranged transversely of

the car at each end of the hopper. Secured to the hopper end floor sheets 24 at a point adjacent the crank frames 22 when in the locked position shown in Figs. 3 and 4, are door tripper shaft bearings 52 in which the inner ends of shafts 50 and 51 are supported and have their bearings. At their outer ends these parallel tripper shafts have a bearing in other brackets 53 which may be secured to the inner longitudinal side sill 14 as shown in Fig. 2. Fixed to the inner ends of the tripper shafts 50 and 51 at points adjacent the shaft bearings 52 on the hopper sheets are mounted the tripping and locking pawls 54 having a tripping arm 55 and a shouldered locking arm 56. The tripping arm 55 is designed to bear against yoke piece 20 to force the yoke piece and connected crank frame 22 beyond the dead center locking position shown in Figs. 3 and 5, while the function of the shouldered locking arm 56 is to prevent such crank frame movement when said arm is interlocked with shouldered locking lug 57 on the yoke piece 20 as shown in Fig. 3. At the outer end of tripper shaft 50 and in position to engage lug 58 on sprocket wheel 37 is fixed a tripper shaft operating arm 59 arranged with its arm substantially parallel to the tripper arm 55 of the tripping and locking pawl 54 mounted on the same shaft, said relative position being clearly indicated in Figs. 3 and 4. On the outer end of tripper shaft 51 is secured the combination connecting rod arm and indicator 60 as best shown in Figs. 1 and 6. This indicator 60 is of a general bell-crank formation and comprises a short arm portion 61 and a longer weighted arm portion 62 overlying the operating shaft 35 as shown on Figs. 1, 2 and 6. Connecting the arm 61 of indicator 60 on the tripper shaft 51 at one end of the car to the operating arm 59 on tripper shaft 50 at the opposite end of the car is a rod 63 for simultaneously communicating the movement of the tripper shaft on one end of the car to the tripper shaft and its parts on the opposite end of the car. Such movement of the tripper shafts is effected automatically by the operation of the crank shaft mechanism through the medium of the operating shaft 35, all arranged as hereinabove described.

Assuming the doors to be in the locked raised position shown in full lines in Figs. 1, 3 and 4, the doors are released to drop the loading by first rotating the pawl shaft 42 by means of the counter-balance handle 43 to disengage locking pawl 41 from the ratchet wheel 40 on the operating shaft 35. The operating shaft 35 being thus released for rotation, the shaft is rotated by means of a lever fitted over a square end thereof. The rotation of the shaft is in the direction of the center of the car causing the link belt 38 to rotate the sprocket wheels 36 and 37 in

relatively opposite directions and away from the hopper end floors 24 as indicated by the arrows in Figs. 7 and 8, respectively.

Prior to the beginning of sprocket wheel movement the crank shafts 30 are locked against rotation by means of the lugs 34 of the sprocket wheels bearing against the lugs 33 of the crank shafts as shown in Figs. 11 and 12. Upon rotation of the sprocket wheels in opposite directions, the lugs 34 on the sprockets first move away from one side of the temporarily stationary crank shaft lugs 33 to the opposite side of said lugs as shown in Figs. 9 and 10. During this movement the sprockets will have rotated idly upon the temporarily stationary crank shafts under the influence of the link belt movement and the crank shafts released to permit rotation thereof.

Continued rotation of the sprockets in the direction indicated by the arrows in Figs. 7 and 8 will cause the lug 58 on sprocket wheel 37 to engage tripper shaft operating arm 59 on tripper shaft 50 causing said shaft to rotate in a direction toward the hopper end floor 24 carrying with it the tripping and locking pawl 54. Since the tripper shafts 50 and 51 are connected by rod 63, the rotative movement of tripper shaft 50 will be communicated to tripper shaft 51 at the opposite end of the car simultaneously and the locking and tripping pawl 54 on the remote tripper shaft 51 will likewise be actuated. Such movement of the tripping and locking pawls 54 will carry their tripping arms 55 into engagement with the respectively adjacent yoke pieces 20 and force the crank frames past their dead center position on the crank shaft 30 after which gravity will operate to cause said crank frames to yield to the weight of the supported load and move to the released position indicated in broken lines in Fig. 4, whereupon the doors will drop to the broken line position indicated in Fig. 1. During the rotation of the tripper shafts the locking arms 56 of the tripping and locking pawls 54 will move away from the path of movement of locking lugs 57 on yoke pieces 20 before the tripping arms 55 will have come into contact with the rear faces of the yoke pieces thereby releasing the crank frames for movement under the pressure of the tripping arms 55. During this period of movement the connecting rod 63, under the influence of the movement of lug 58 of sprocket wheel 37 against operating arm 59 on tripping shaft 50, will move in a direction away from the tripping shaft 51 at the opposite end of the car and carry with it crank arm portion 61 of the indicator 60 causing the indicator arm 62 to rise thereby indicating to the operator that the mechanism is unlocked and in condition to permit the release of the doors.

To raise the doors, the counter-balance

handles 43 are drawn back from their unlocking position shown in dotted lines in Fig. 1 to their initial ratchet locking position shown in full lines in that figure. This movement rotates the pawl shaft 42 and carries the ratchet pawl into engagement with the ratchet wheel and locks the operating shaft 35 against rotation in the opposite direction during the door raising operation. The operating shaft 35 is then rotated in a direction away from the hopper to effect a reverse movement of the link belt 38 causing the rotation of the sprocket wheels in the direction indicated by the arrows in Figs. 11 and 12. Continuing thus to rotate, the operating shaft 35 will cause the sprocket wheel lugs 34 to exert a driving force against crank shaft lugs 33 and cause said shafts to rotate to return the crank frames 22 and the doors to their raised and locked positions indicated in Figs. 1, 2, 3 and 4.

During the movement of the sprocket wheels 36 and 37 in the direction indicated by the arrow in Figs. 11 and 12, the lug 58 on sprocket wheel 37 will have moved away from the operating arm 59 of tripping shaft 50 and allowed the weighted indicator arm 62 to drop to the position indicated in Fig. 6 and to reverse the movement of connecting rod 63 under the power of the crank arm 61 of the indicator, which movement will cause the operating arm 59 to return to its initial position as indicated in Fig. 3. This movement of indicator 60 and operating arm 59 under the influence of the force exerted by the weight of indicator arm 62 will cause the reverse rotation of their respective shafts 51 and 50 and force the shouldered locking arms 56 of the tripping and locking pawls 54 into the path of and subsequent engagement with the shouldered locking lug 57 on the yoke piece 20 and simultaneously moving the tripping arms 55 out of engagement with said yoke pieces. In this position of the parts the mechanism is locked against premature release, due to possible failure of the crank frame mechanism to assume its full dead center locking position on the crank shafts.

From the foregoing it will be noted that there has been provided a releasing and locking mechanism simple in construction and positive in its operation, the releasing and locking assembly being operable automatically through the medium of the movement of the lost motion devices of the door operating mechanism.

What I claim is:

1. A hopper car having a single discharge opening and a pair of drop doors closing said opening, crank shaft mechanism adjacent the ends of the doors, an operating shaft, lost motion devices between said operating shaft and crank shaft mechanism and

- means operated by said lost motion devices to lock and release said crank shaft mechanism.
2. A door operating mechanism for hopper car doors arranged longitudinally of the car and including crank shaft mechanism adjacent the opposite ends of said doors, an operating shaft, lost motion devices between said operating shaft and crank shaft mechanism, and locking and unlocking mechanism for said crank shaft mechanism automatically actuated by said lost motion devices.
3. In a door operating mechanism for drop doors, crank shafts connected to the ends of said doors, lost motion devices on said shafts, and crank shaft locking and releasing mechanism automatically actuated by said lost motion devices.
4. In a door-operating mechanism for cars having a pair of drop doors, crank mechanism including lost motion devices adjacent the opposite ends of said doors and locking and releasing mechanism comprising a pair of tripper shafts respectively adjacent the crank mechanism, tripping and locking pawls fixed to said tripper shafts in position to engage the crank mechanism and adapted to automatically unlock and release said crank mechanism upon actuation of said tripper shafts.
5. In a door operating mechanism for drop doors, crank shaft mechanism connected to the ends of said doors, lost motion devices on said shafts, and tripping and releasing mechanism adapted to be automatically actuated by said lost motion devices and including a pair of tripper shafts respectively adjacent the crank shaft mechanism, a pawl fixed to the respective inner ends of said tripper shafts and provided with locking and tripper arms adapted to alternately engage and disengage the crank shaft mechanism.
6. The combination with the drop doors of a hopper car having a single discharge opening, crank shaft mechanism adjacent the opposite ends of said doors, an operating shaft, lost motion devices between said crank shaft mechanism and operating shaft, and releasing and locking mechanism including a pair of tripper shafts respectively adjacent said crank shaft mechanism and provided with a tripping and locking pawl fixed to one end thereof, said releasing and locking mechanism being automatically actuated by said lost motion devices.
7. In a dumping car, dumping doors, door-operating mechanism for raising said doors having a lost motion device therein and a locking means for said door-operating mechanism operated by said lost motion device to release said door-operating mechanism.
8. In a dumping car, dumping doors, a crank shaft operatively connected to said doors, an operating means for said crank shaft having a lost motion connection therewith and a locking means for said crank shaft operated by said crank shaft operating means during the free movement thereof to release said crank shaft.
9. In a dumping car, dumping doors, a crank shaft operatively connected to said doors, a locking means for said crank shaft having a lost motion connection therewith adapted to operate said locking means to release said crank shaft during said lost motion and means to operate said crank shaft to drop said doors during the release movement of said locking means.
10. A door-operating mechanism comprising parts having a lost motion connection and a lock preventing movement of one of said parts until disengaged from said part by the operation of the other of said parts during the free movement thereof.
11. A door-operating mechanism comprising parts having a lost motion connection and locking and tripping means for one of said parts operated by the other of said parts during the free movement thereof to first release and then operate said first part.
12. A door-operating mechanism comprising parts having a lost motion connection and a lock for one of said parts operated by the other of said parts during the free movement thereof to release said first part, and means automatically returning said lock to locking position upon reverse movement of said other part.
13. In a door-operating mechanism, a crank shaft operatively connected to the door, a locking and tripping mechanism for said crank shaft and operating means for said crank shaft having a lost motion connection therewith adapted to operate said locking and tripping means during the free movement of said operating means.
14. In a door-operating mechanism, a crank shaft operatively connected to the door, means to operate said crank shaft to raise the door having a lost motion connection therewith and locking and tripping means for said crank shaft operated by said shaft operating means to release and operate said shaft to open the door during the free movement of said shaft operating means.
15. In a door-operating mechanism, a crank shaft operatively connected to the door, an operating means for said crank shaft having a lost motion connection therewith and a lock for said crank shaft operated to release said crank shaft and a tripping means operated to cause operation of said crank shaft by said operating means during the free movement thereof.
16. In a door-operating mechanism, a crank shaft operatively connected to the

door, an operating means for said crank shaft having a lost motion connection therewith and a lock for said crank shaft operated to release said crank shaft and a tripping means operated to cause operation of said crank shaft by said operating means during the free movement thereof, said lock and said tripping means being automatically restored upon the operation of said crank shaft by said operating means.

17. A door-operating mechanism comprising means connected to the door, operating mechanism connected to said means by a lost motion connection and a lock for said means operated by said mechanism.

18. A door-operating mechanism comprising means pivotally connected to the door, operating mechanism connected to said means by a lost motion connection and a lock engaging said means controlled by said operating mechanism.

19. A door-operating mechanism comprising means connected to the door, mechanism to operate said means to raise the door and a tripping device operated by said mechanism to operate said means to drop the door.

20. A door-operating mechanism comprising means connected to a door, mechanism to operate said means to raise the door and a lock and tripping device adapted to hold the door in raised position and operated by said mechanism to release the door and operate said means to drop the door.

21. A door-operating mechanism comprising means having a lost motion connection therein and a lock for the door engaging said door operating mechanism and operated by said means during said lost motion.

22. A door-operating mechanism comprising means having a lost motion connection therein and a lock and tripping device for

the door operated by said means during said lost motion to release the door and cause the door to drop.

23. A door-operating mechanism comprising means having a lost motion connection therein and a door-tripping device operated during said lost motion to initiate the opening of the door, said means being operative to open said door upon taking up lost motion upon failure of said tripping device.

24. In a dumping car, a dumping door, operating mechanism for said door and a door-tripping device operated by said mechanism to initiate the opening of said door, said means being operative to open said door upon failure of said tripping device.

25. In a dumping car, a dumping door, means operative to raise said door and a lock and tripping device for said means operated by said means, said lock being disengaged prior to the engagement of said tripping device with said means.

26. In a dumping car, a dumping door, means operative to raise said door and a locking device for said means and tripping device for said means operated by said means, said locking and tripping devices engaging said means alternatively.

27. In a dumping car, a dumping door, means operative to raise said door and a locking device for said means disengaged from said means by the operation of said means.

28. In a dumping car, a dumping door, means operative to open and close said door having a lost motion connection therein and a door tripping device operated by said means to initiate the opening of said door during said lost motion.

In witness whereof I have hereunto set my hand.

VICTOR WILLOUGHBY.
